(57) **CLAIM**

The ornamental design for a vanity as shown and described.

DESCRIPTION

FIG. 1 is a perspective view taken from the front, left, and top of a vanity of the present application;

FIG. 2 is a perspective view taken from the rear, right, and bottom thereof;

FIG. 3 is a top view thereof;

FIG. 4 is a front view thereof;

FIG. 5 is a right side view thereof; and,

FIG. 6 is a left side view thereof.

The bottom, pulls, and caster wheels are shown in broken line to illustrate the vanity. All broken lines form no part of the claimed design.
